UNITED STATES PATENT OFFICE.

ERIK AUGUST BOLINDER, OF STOCKHOLM, SWEDEN.

DOVETAILED STAVE FOR BARRELS AND CASKS.

Application filed August 21, 1925, Serial No. 51,715, and in Sweden August 21, 1924.

In assembling barrels and casks having dove-tailed staves the assembling must be effected so that parts of the joint having a dove-tailed cross section are slid onto each other in the longitudinal direction thereof. This sliding together of the staves generally brings about great friction between the parts of the joint, and, in fact, the resistance produced may be so appreciable that the parts 10 of the joint are caused to break.

The present invention has for its purpose to obviate this drawback, and the invention is principally characterized by the fact that the width of the parts of the joint decreases 15 toward the one end of the stave.

The accompanying drawing illustrates the arrangement as applied onto a curved stave intended for bulged barrels and casks. Fig. 1 shows the stave in an edgewise view, and 20 Fig. 2 is a cross sectional view thereof.

The edges of the parts 1 and 2 of the joint do not parallel each other but are at one end of the stave situated at a greater distance from one another than at the other 25 end of the stave, that is to say, they are of a wedge-like shape. This arrangement facilitates sliding the parts of the joint onto each other along the major portion of their

length, without any appreciable friction or breaking strains being produced thereby, 30 which, on the other hand, will be the case if the edges of the parts of the joint parallel one another. Only after the wedge-shaped parts of the joint have been slid onto each other along the major portion of their 35 length will the resistance be produced which is then overcome by driving the staves forcibly together in the longitudinal direction. By reason of the cross sectional outline of the parts of the joint the said forcible 40 driving together of the staves will cause so powerful a wedge action in the transversal direction of the staves that the latter will be pulled tightly onto each other.

What I claim as new and desire to secure 45 by Letters Patent of the United States of America is:

A dove-tailed stave for producing barrels and casks, characterized by the fact that the parts of the stave joints decrease in width 50 along the stave, from the one end of the stave toward the other, for the purpose of facilitating the sliding of the parts of the joint together.

In testimony whereof I affix my signature.

ERIK AUGUST BOLINDER.
